US00D707276S

(12) **United States Design Patent**
Norman et al.

(10) **Patent No.:** US D707,276 S
(45) **Date of Patent:** ** Jun. 17, 2014

(54) **ROBOTIC MICO-CONTROLLER**

(71) Applicant: **Innovation First, Inc.**, Greenville, TX (US)

(72) Inventors: **David Anthony Norman**, Greenville, TX (US); **Robert H. Milmitch, III**, Rowlett, TX (US); **Paul David Copioli**, Rockwall, TX (US); **Gregory James Lavender**, Rockwall, TX (US); **Aren Calder Hill**, Rockford, IL (US); **Douglas Michael Galletti**, Allen, TX (US); **John Edward Vielkind-Neun**, Rockwall, TX (US); **Arthur Philip Dutra, IV**, Greenville, TX (US)

(73) Assignee: **Innovation First, Inc.**, Greenville, TX (US)

(**) Term: **14 Years**

(21) Appl. No.: **29/451,416**

(22) Filed: **Apr. 2, 2013**

(51) LOC (10) Cl. **15-99**
(52) U.S. Cl. **USPC D15/199**

(58) **Field of Classification Search**

USPC D15/199; 74/490.01, 490.02, 490.03, 74/490.05; 137/624.11; 239/69; 315/152, 315/158; 318/560; 361/622, 627, 628, 643; 700/99, 284; 702/150

(57) **CLAIM**

The ornamental design for a robotic mico-controller, as shown and described.

DESCRIPTION

FIG. 1 is a front-top perspective view of a robotic mico-controller;

FIG. 2 is a rear-side perspective view of FIG. 1;

FIG. 3 is a front-bottom perspective view of FIG. 1;

FIG. 4 is a top side view of FIG. 1;

FIG. 5 is a bottom side view of FIG. 1;

FIG. 6 is a right side view of FIG. 1;

FIG. 7 is a left side view of FIG. 1;

FIG. 8 is a front side view of FIG. 1; and,

FIG. 9 is a rear side view of FIG. 1.

The surface lines are for the purpose of illustrating portions of the environmental structure and forms no part of the claimed embodiments and design.
